(57) **CLAIM**

The ornamental design for a wireless keyboard for tablet, as shown and described.

DESCRIPTION

FIG. 1 is a front, right perspective view of a wireless keyboard for tablet showing my new design;
FIG. 2 is a top right perspective view thereof;
FIG. 3 is a rear top perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 a perspective view thereof, shown in an alternate position; and,
FIG. 11 is a perspective view thereof, showing the cover in a closed position.
